UNITED STATES PATENT OFFICE.

JOSEPH E. DUKE, OF BIRMINGHAM, ALABAMA.

COUPLING FOR MINE-CARS.

1,401,890.

Specification of Letters Patent. Patented Dec. 27, 1921.

Application filed March 29, 1921. Serial No. 456,580.

To all whom it may concern:

Be it known that I, JOSEPH E. DUKE, a citizen of the United States, residing at Birmingham, in the county of Jefferson 5 and State of Alabama, have invented certain new and useful Improvements in a Coupling for Mine-Cars; and I do hereby declare the following to be a full, clear, and exact description of the invention, 10 such as will enable others skilled in the art to which it appertains to make and use the same.

The object of the invention is to provide a simple and inexpensive automatic coupler 15 for mine cars adapted to permit of the necessary relative range of movement of the male and female coupler members while insuring the efficient engagement thereof when the members are brought together; 20 furthermore to provide simple and efficient means for locking the movable knuckle of the female member in its closed position; to provide efficient means for preventing the jamming of the members together in the 25 event of the sudden stoppage of the forward car of a train or in traversing down-grades, and to provide efficient means for connecting the coupler members to the opposite ends of a car; and with these objects in view the 30 invention consists in a construction and combination of parts of which a preferred embodiment is illustrated in the drawing, wherein:

Figure 1 is a plan view of a pair of 35 coupler members arranged in engaged relation.

Fig. 2 is a longitudinal vertical sectional view of the same.

Fig. 3 is a side view of the coupler members carried at opposite ends of a car to 40 show the connection between the same, the car body being indicated in dotted lines.

Fig. 4 is a detail sectional view on the plane indicated by the line 4-4 of Fig. 1 45 to show particularly the relation between the latch and the movable knuckle and a means on the rocker shaft for tripping the latch.

Fig. 5 is a front or face view partly broken 50 away of the female member of the coupler.

Fig. 6 is a detail view in perspective of the male member of the coupler.

The male and female coupler members 10 and 11, as applied respectively to the opposite 55 ends of a mine car indicated at 12, are provided at their inner end with sockets 13

and 14 for the reception of the extremities, respectively, of a draw bar 15 which extends longitudinally throughout the length of the car and secured by vertical bolts 16 60 and 17, so as to relieve the body of the car of strain incident to the engagement of the coupler members and the draft in moving the cars when coupled to form a train.

The female coupler member is provided 65 with a flared throat 18, at the upper and lower sides of the reduced opening at the inner end of which are arranged the movable knuckles 19 and wall 20 which are preferably rounded to facilitate the engagement therewith of the head 21 on the extremity of the tongue 22 forming a part of the wall coupler head, a cross head 23 being arranged at the base of the tongue for contact with the forward edges of the flared 75 throat of the female member. In the construction illustrated the cross head is of generally triangular form arranged in a vertical plane with its base presented forwardly for engagement with the throat of 80 the complementary coupler member as shown clearly in Fig. 2. The terminal head of the tongue 22 is preferably of substantially elliptical form in plan to permit of a lateral swinging movement of the tongue, with 85 in the area mounted by the side walls of the throat 18, upon the inner surfaces of the knuckles as a fulcrum, and said head is also preferably reduced vertically in thickness toward its forward edge to facilitate 90 separation of the knuckles by movement of the upper knuckle in engaging the coupler members.

The movable coupler knuckle is fulcrumed by means of a transverse pivot pin 24 and 95 carries a wing 25 having a slot 26 with a transverse pin 27 for engagement by an uncoupling arm 28 on the rock shaft 29. The rock shaft is arranged transversely of the coupler member 11, being mounted in bearings 30 in the upper edges of the side walls thereof and being retained in place by the cap plate or cover 31 which is removable to give access to the operating elements when adjustment or repair becomes necessary. 100 105

The free or inner edge of the wing 25 of the movable knuckle is preferably beveled or reduced as indicated at 32 for engagement by a latch 33 pivoted as at 34 to a side wall of the coupler member and weighted as at 35 to hold the latch yieldingly and normally in engaging relation with the bevel-

eled or reduced edge of the knuckle wing. At its upper edge the latch is provided with a shoulder 36 for engagement by a trip finger 37 also carried by the rock shaft 29, so 5 that when said shaft, which is provided terminally with handles or crank arms 38 is turned to raise the free edge of the wing 25 said trip finger tilts the latch sufficiently to release the wing, and thereupon the latch 10 returns to its normal position under the influence of its actuating weight or counter-balance to occupy a position in the path of the wing to hold the knuckle in an open or receiving position. As soon as the complemental coupler member enters the opening at the inner end of the throat 18 however, and thereby positions the terminal head 21 of the tongue 22 within the coupler chamber behind the movable knuckle, a 15 slight strain upon the male coupler member tending to separate the members will cause the knuckle 19 to swing to its locking position with the wing 25 engaged by the latch 33. The uncoupling of the member 20 cannot thereafter be accomplished except by the operation of the uncoupling or rock shaft.

From the description it will be obvious that while an efficient engagement may be 30 secured between the complemental members of the coupler and may be secured merely by bringing said members into engaging relation, the elements entering into the construction are of such simplicity as to practically eliminate the risk of disarrangement 35 or breakage notwithstanding the rough usage to which mine cars ordinarily are subjected, and in the event of injury or disarrangement, repairs may readily and quickly 40 be made without the necessity of resorting to skilled service.

Having thus described the invention, what I claim is:—

1. A car coupling having complemental

coupling members, one of said members having a knuckle, the other of said members having a tongue engageable with said knuckle, means pivotally mounting the knuckle to yield relatively to the tongue to lock the latter, means operable to shift the 45 knuckle to release the tongue, a latch normally in engagement with said knuckle, and trip means to release the latch as said last mentioned means is operated.

2. An automatic coupler for cars and the like having complemental male and female members of which the latter is provided with a knuckle and the former is provided with a terminally headed tongue for engagement with said knuckle, said knuckle 50 being movable upon a horizontal axis and having a rearwardly extending wing, and an uncoupling shaft having an arm for engagement with said wing, in combination with a latch yieldingly held in engaging relation with the wing to secure said knuckle 55 in its engaging position.

3. An automatic coupler for cars and the like having complemental male and female members of which the latter is provided with a knuckle and the former is provided with a terminally headed tongue for engagement with said knuckle, said knuckle 60 being movable upon a horizontal axis and having a rearwardly extending wing, and an uncoupling shaft having an arm for engagement with said wing, in combination 65 with a latch yieldingly held in engaging relation with the wing to secure said knuckle in its engaging position, and a trip finger 70 on the uncoupling shaft for tilting the latch 75 to release the wing of said knuckle.

In testimony whereof I affix my signature in presence of two witnesses.

JOSEPH E. DUKE.
